UNITED STATES PATENT OFFICE

159,101

COMBINED SCOOP AND DISPENSER

Edward San Giovanni, Ridgefield, Conn.

Application January 19, 1949, Serial No. 335

Term of patent 3½ years

(Cl. D44—29)

To all whom it may concern:

Be it known, that I, Edward San Giovanni, a citizen of the United States of America, residing at Ridgefield, in the county of Fairfield and State of Connecticut, have invented certain new, original, and ornamental Design for a Combined Scoop and Dispenser, of which the following is a specification, reference being had to the accompanying drawing, constituting a part hereof.

Fig. 1 is a side elevational view of a combined scoop and dispenser, showing my new design; and

Fig. 2 is a top plan view.

I claim:

The ornamental design for a combined scoop and dispenser, substantially as shown.

EDWARD SAN GIOVANNI.
